CLAIM

The ornamental design for a cooking cradle, as shown and described.

DESCRIPTION

FIG. 1 is a perspective view of my new design;

FIG. 2 is a top view thereof;

FIG. 3 is a bottom view thereof;

FIG. 4 is a front view thereof;

FIG. 5 is a rear view thereof;

FIG. 6 is a left end view thereof; and,

FIG. 7 is a right end view thereof.

The evenly broken lines represent parts of the article. The dot-dash lines represent the boundaries of the claim. None of the broken lines form part of the claimed design.

1 Claim, 6 Drawing Sheets
